UNITED STATES PATENT OFFICE.

SETH A. CRONE, OF EAST ORANGE, NEW JERSEY, ASSIGNOR TO BUFFALO BRAKE BEAM COMPANY, OF NEW YORK, N. Y., A CORPORATION OF NEW YORK.

RAILWAY BRAKE BEAM.

Application filed August 15, 1924. Serial No. 732,169.

To all whom it may concern:

Be it known that I, SETH A. CRONE, a citizen of the United States, and a resident of East Orange, in the county of Essex and State of New Jersey, have invented certain new and useful Improvements in Railway Brake Beams, of which the following is a specification.

The invention pertains to railway brake-beams, and particularly to a four-point suspension, therefore, and to guards extending longitudinally of the car-truck and above the brake-beams and cooperating with the respective carrier or suspension bars for holding the beams captive, while at the same time permitting the beams to have their requisite movements in the service application of the brakes to and their release from the car wheels.

The invention resides in certain improvements on the constructions shown and described in my Letters Patent No. 1,719,762, dated December 16, 1924, and No. 1,519,764, dated December 16, 1924, wherein are shown carrier or suspension bars and cooperating safety guard bars secured to the spring plank of the car-truck. In the said patent the guard bars are integral with each other. In accordance with my present invention the guard bars are independent of each other and with the respective carrier or suspension bars to which they are connected, are adjustable longitudinally to bring the inclined surfaces of the carrier or suspension

bars into correct relation to the truss rods of the brake-beams, thereby adapting the carrier or suspension bars to meet variations in the position or height of truss rods due to variations in the condition of brake-beam hangers and other causes. My present invention also involves novel means for securing the inner end portions of the safety guard bars and the inner end portions of the carrier or suspension bars to the spring plank of the car-truck; whereby said guard bars and carrier or suspension bars may be conveniently and efficiently secured in position and are rendered longitudinally adjustable and capable of convenient removal whenever it may be desired to remove a brake-beam from the truck.

The invention will be fully understood from the detailed description hereinafter presented, reference being had to the accompanying drawings, in which:

Fig. 1 is a vertical longitudinal section through a portion of a car-truck equipped with the features of my invention, the section being on the dotted line 1—1 of Fig. 5;

Fig. 2 is a vertical longitudinal section, on a larger scale, through a portion of the same, taken on the dotted line 2—2 of Fig. 5;

Fig. 3 is a vertical transverse section, on a larger scale, through a portion of the same, taken on the dotted line 3—3 of Fig. 5;

Fig. 4 is a detached perspective view showing a modified construction of one feature of the invention;

Fig. 5 is a top plan view, partly broken away, of a car-truck equipped with the features of my invention;

Fig. 6 is a vertical transverse section through a portion of the same, taken on the dotted line 6—6 of Fig. 5, and

Fig. 7 is a detached top view of a lower bracket secured to the spring plank of the truck for supporting the inner end portions of the carrier or suspension bars.

In the drawings, 10 designates a portion of a well-known channel-form of spring plank constituting a portion of a car-truck frame of usual type, and 11, 12 indicate portions of inside hung trussed brake-beams of customary type, each comprising the usual compression member 13, tension member 14 and strut 15. The brake-beams are suspended by well-known pivoted hangers, not shown, and carry the brake-shoes, not shown, as usual.

My invention does not involve any change in the brake-beams, their shoes or their hangers, which form two points of the suspension.

My invention pertains more especially to the carrier or brake-beam suspension bars 16, 17, which are duplicated at opposite sides of the truck, as usual, and form two means or points of suspension for the brake-beams, to the safety guard bars 18, 19, extending over the brake-beams and detachably connected at their outer ends with the outer ends of said carrier or suspension bars; said bars 18, 19, being duplicated at opposite sides of the car-truck, to the means provided for securing the inner end portions of the suspension bars against the bottom of the spring plank and to the means provided for securing the inner end portions of the safety guard bars upon the top of said spring plank.

The carrier or suspension bars 16, 17 correspond with each other but in service extend longitudinally in opposite directions, as shown, and said bars are preferably of inverted channel shape in cross section and present convex upper surfaces. The bars 16, 17 have straight horizontal inner end portions and thence said bars incline upwardly and outwardly below and to receive and direct the tension members 14 of the brake-beams, the outer ends of said bars 16, 17 being detachably connected with the outer ends of the safety guard bars 18, 19, by means of pins 20 which extend through matching sleeve members formed on the adjacent ends of the bars 16, 18 and bars 17, 19, as shown. The bars 16, 17 are substantially disclosed in my Letters Patent No. 1,519,762, dated December 16, 1924, and Letters Patent No. 1,519,764, dated December 16, 1924.

The safety guard bars 18, 19 correspond with each other but in service extend longitudinally in opposite directions, as shown, and said bars are preferably of inverted channel shape in cross section and present convex upper surfaces. The bars 18, 19 have straight horizontal inner end portions and thence said bars extend upwardly along the inner sides of the side flanges of the spring plank and thence longitudinally above the brake-beams 11, 12 to the outer ends of the carrier or suspension bars 16, 17, to which they are secured, as aforesaid. The safety guard bars 18, 19 are substantially disclosed in my aforesaid Letters Patent, except that in said Letters Patent the said bars are integral with each other or constitute parts of a single bar, whereas in the present instance said bars 18, 19 are each in a separate piece and capable of independent adjustment and independent removal when necessary.

The means for securing the inner end portions of the bars 16, 17 to the spring plank 10, comprise a durable bracket 21 containing longitudinal channels 22, 23 for the inner end portions of the respective bars 16, 17 and having laterally extending flanges 24 to engage the bottom of the spring plank, a central upwardly pressed transverse strip 25 which also engages the spring plank and at its ends affords abutments, when necessary, for the inner ends of the bars 16, 17, longitudinal shoulders or seats 26 for the depending side edges of the bars 16, 17, and longitudinal elevated seats 27 for the concave lower surfaces of the bars 16, 17. The brackets 21 are secured to the spring plank 10 by means of rivets 28 which extend vertically through said plank and through the flanges 24 of said brackets. At its ends each bracket 21 is flanged downwardly, as at 29. The formation of the bracket 21 is one which results in the production of a bracket

of great strength and efficiency. The bracket-channels 22, 23 are open at their outer ends and said channels closely receive the inner end portions of the carrier or suspension bars 16, 17, which while firmly fitting the channels may be forced into and from said channels and also be adjusted longitudinally therein, as occasion may require. One feature of the present invention resides in the fact that each carrier or suspension bar, with its guard bar, may be adjusted longitudinally to meet the requirements of the brake-beam and especially the position of the truss-rod thereof. In Figs. 1 and 2 the carrier bars, with their respective guard bars, are shown as having been adjusted outwardly to correctly position the inclined surfaces of the carrier bars at a suitable height to meet the position of the truss rods. The position of brake-beams varies somewhat with the condition of the pivoted brake-hangers and other causes and the inclined surfaces of the carrier bars should have a definite relation to the truss rods of the beams in their small variations of position, and hence I provide for the longitudinal adjustment of said bars. If the carrier bars and guard bars should not in the position shown in Figs. 1 and 2, meet the requirements of the truss rods of a different set of brake-beams, said bars would be adjusted inwardly to bring a more elevated portion of the inclined surface of the carrier bars below the truss rods. By having the guard bars 18, 19 in independent parts as distinguished from being integral with each other, the carrier bars 16, 17 may be adjusted longitudinally in the manner just explained. When the carrier bars require no adjustment with relation to the truss rods, the inner ends of said bars will abut against the opposite edges of the abutment strip 25, this being the initial position of said bars and the correct one with regard to brake-beams having a standard position.

The means shown for securing the horizontal inner end portions of the safety guard bars against the upper surface of the spring plank 10 comprise two parallel longitudinally extending angle bars 30, 31, two transverse locking pins 32, 33, a bridge piece 34 upon the upper surfaces of adjacent portions of the guard bars and crossing the joint between said portions and, preferably, a lock 35 for securing said pins 32, 33 against accidental loss in the event of the breakage or loss of the cotter keys 36 with which said pins are equipped.

The angle bars 30, 31 have their flanges 37 seated upon the spring plank 10 and extended transversely in opposite directions so as to leave a clear space between their vertical flanges 38 to closely receive the width of and house the inner end portions of the guard bars 18, 19. The angle bars 30,

31 are secured to the spring plank by the same rivets 28 by which the bracket 21 is secured against the lower surface of said plank. The vertical flanges 38 extend suitably above the thickness of the bars 18, 19 and receive the aforesaid pins 32, 33. The bridge piece 34 is a steel bar and is bowed upwardly along its longitudinal center and said bridge piece is placed upon the adjacent 10 inner end portions of the bars 18, 19 and is engaged by and flexed downwardly against the bars 18, 19 by means of said pins 32, 33.

The vertical flanges 38 of the angle bars 30, 31 are formed with transverse machined 15 apertures 39 (Fig. 3) to efficiently receive the pins 32, 33, and said pins are straight and fit into said apertures and on one end have a head 40, while at their other end said pins are tapered, as at 41, and apertured to receive a cotter key 36. The tapered ends 41 of the pins 32, 33 permit of 20 said pins when the same are driven to position, to act as wedges against the bridge piece 34 for flexing the bowed portion thereof downwardly and firmly binding said bridge piece against the adjacent portions of the bars 18, 19, whereby said bars become very firmly secured in position against the upper surface of the spring plank and 25 between the angle bars 30, 31.

In Fig. 2 a space is shown between the adjacent ends of the bars 18, 19 and this is due to the fact that said bars are shown as having been, with the carrier bars 16, 17, 30 adjusted outwardly, as hereinbefore explained. In the initial position of the bars 18, 19 their inner ends abut against each other at the same time that the inner ends of the bars 16, 17 abut against the abutment strip 25.

The bars 18, 19 and bars 16, 17 may be adjusted to meet the requirements of the 35 brake-beam truss-rods before the pins 32, 33 are applied to position, and at any time either of the suspension bars 16, 17 may, with its guard bar, be adjusted longitudinally on removing one or the other of the pins 32, 33. The guard bars 18, 19 may be conveniently and securely applied to position by the means described, and also may be conveniently removed from the spring plank on the withdrawal of the pins 32, 33. I employ the bridge piece 34 as an auxiliary expedient to aid in securing the bars 18, 19, 40 and if the bridge piece should be omitted, as it would be if the bars 18, 19 were integral with each other, as in my aforesaid applications, the pins 32, 33 would be positioned to directly engage the upper surfaces of said bars.

The angle bars 30, 31 form a channel to snugly receive the inner end portions of the bars 18, 19, and I present Fig. 4 to indicate that this channel may be formed from an 45 integral blank cut and bent to form par-

allel vertical flanges 42 to receive the bars 18, 19 and base members 43 apertured to receive the rivets 28. The flanges 42 are centrally apertured, at 44, to receive a locking pin 32 or 33, it being possible to secure 70 the bars 18, 19 by means of one pin instead of two, although it is preferable to employ two locking pins.

Each pin lock 35 consists of a strip of sheet steel having a body portion 45, right angularly bent end portions 46, 47 apertured to permit the pin 32 or 33 to pass through them and a part 48 extending from the outer end of the portion 46, as shown in Fig. 6, 75 and adapted to be bent over against the head of the pin, as shown in Fig. 3, and avoid any danger of the loss of the pin in the event that the cotter key 36 should become damaged or displaced. The lock 35 bridges over both flanges 38 and the bar between said flanges. The details of the pin lock 35 are fully disclosed in my pending application for Letters Patent Serial No. 729,692 filed August 2, 1924.

It is believed that the operation of the mechanism hereinbefore described will be fully understood from the explanation given thereof in connection with the description of the various details of said mechanism.

It will be understood that the carrier or suspension bars and guard bars, with the means securing them, will be duplicated at opposite sides of the truck.

What I claim as my invention and desire to secure by Letters Patent, is:

1. In a car-truck having a spring plank and inside hung brake-beams, inclined carrier or suspension bars for said beams, said bars having horizontal inner end portions extending below the spring plank, safety guard bars extending from the spring plank above the brake beams and connected at their outer ends with the outer ends of the carrier bars, said guard bars having horizontal inner end portions at the upper surface of the spring plank, supporting means below the spring plank for detachably receiving the inner end portions of the carrier bars and clamping means at the upper side of the spring plank releasably securing the inner end portions of said guard bars thereto.

2. In a car-truck having a spring plank and inside hung brake-beams, inclined carrier or suspension bars for said beams, said bars having horizontal inner end portions extending below the spring plank, safety guard bars extending from the spring plank above the brake beams and connected at their outer ends with the outer ends of the carrier bars, said guard bars having horizontal inner end portions at the upper surface of the spring plank, supporting means below the spring plank for detachably re-

ceiving the inner end portions of the carrier bars and clamping means at the upper side of the spring plank releasably securing the inner end portions of said guard bars thereto, said carrier bars, with their respective guard bars, being longitudinally adjustable for the purpose of meeting the mounting of the brake-beam.

3. In a car-truck having a spring plank and inside hung brake-beams, inclined carrier or suspension bars for said beams, said bars having horizontal inner end portions extending below the spring plank, safety guard bars extending from the spring plank 10 above the brake beams and connected at their outer ends with the outer ends of the carrier bars, said guard bars having horizontal inner end portions at the upper surface of the spring plank, supporting means 15 below the spring plank for detachably receiving the inner end portions of the carrier bars and clamping means at the upper side of the spring plank releasably securing the inner end portions of said guard bars thereto, said supporting means being a bracket secured to the spring plank and having open channels in its end portions to snugly admit and permit the withdrawal therefrom of the inner end portions of the 20 carrier bars.

4. In a car-truck having a spring plank and inside hung brake-beams, inclined carrier or suspension bars for said beams, said bars having horizontal inner end portions extending below the spring plank, safety guard bars extending from the spring plank above the brake beams and connected at their outer ends with the outer ends of the carrier bars, said guard bars having horizontal inner end portions at the upper surface of the spring plank, supporting means 35 below the spring plank for detachably receiving the inner end portions of the carrier bars and clamping means at the upper side of the spring plank releasably securing the inner end portions of said guard bars thereto, said supporting means being a bracket secured to the spring plank and having open channels in its end portions to snugly admit and permit the withdrawal therefrom of the inner end portions of the carrier bars, and said bracket having at the inner ends of 40 said channels an abutment for the inner ends of said carrier bars.

5. In a car-truck having a spring plank and inside hung brake-beams, inclined carrier or suspension bars for said beams, said bars having horizontal inner end portions extending below the spring plank, safety guard bars extending from the spring plank above the brake beams and connected at their outer ends with the outer ends of the carrier bars, said guard bars having horizontal inner end portions at the upper surface of the spring plank, supporting means 50

below the spring plank for detachably receiving the inner end portions of the carrier bars and clamping means at the upper side of the spring plank releasably securing the inner end portions of said guard bars thereto, the horizontal inner end portions of said carrier bars and said guard bars being of such length with respect to the width of the spring plank and the length of said supporting means and said clamping means as 70 to permit of the longitudinal adjustment of the carrier bars, with their respective guard bars, for the purpose of meeting the mounting of the brake-beams.

6. In a car-truck having a spring plank and inside hung brake-beams, inclined carrier or suspension bars for said beams, said bars having horizontal inner end portions extending below the spring plank, safety guard bars extending from the spring plank 80 above the brake beams and connected at their outer ends with the outer ends of the carrier bars, said guard bars having horizontal inner end portions at the upper surface of the spring plank, supporting means 85 below the spring plank for detachably receiving the inner end portions of the carrier bars and clamping means at the upper side of the spring plank releasably securing the inner end portions of said guard bars 90 thereto, said clamping means comprising vertical parallel flanges secured upon the spring plank and adapted to snugly receive between them the inner end portions of the guard bars, a bridge piece lying upon said 95 portions of the guard bars and transverse pins extending through said flanges and forcibly bearing against said bridge piece.

7. In a car-truck having a spring plank and inside hung brake-beams, inclined carrier or suspension bars for said beams, said bars having horizontal inner end portions extending below the spring plank, safety guard bars extending from the spring plank above the brake beams and connected at 105 their outer ends with the outer ends of the carrier bars, said guard bars having horizontal inner end portions at the upper surface of the spring plank, supporting means below the spring plank for detachably receiving the inner end portions of the carrier bars and clamping means at the upper side of the spring plank releasably securing the inner end portions of said guard bars thereto, said clamping means comprising vertical 110 parallel flanges secured upon the spring plank and adapted to snugly receive between them the inner end portions of the guard bars, a bridge piece lying upon said portions of the guard bars and transverse pins extending through said flanges and forcibly bearing against said bridge piece, said bridge piece being upwardly bowed along its 115 longitudinal center and said pins being tapered on their forward ends and having 120

125

130

heads on their other ends and being adapted to flex the bridge piece downwardly against the guard bars.

8. In a car-truck having a spring plank and inside hung brake-beams, inclined carrier or suspension bars for said beams, said bars having horizontal inner end portions extending below the spring plank, safety guard bars extending from the spring plank above the brake beams and connected at their outer ends with the outer ends of the carrier bars, said guard bars having horizontal inner end portions at the upper surface of the spring plank, supporting means below the spring plank for detachably receiving the inner end portions of the carrier bars and clamping means at the upper side of the spring plank releasably securing the inner end portions of said guard bars thereto, said clamping means comprising parallel angle bars having outwardly extending horizontal flanges secured upon the spring plank and vertical flanges receiving between them the inner end portions of the guard bars, a bridge piece lying upon said portions of the guard bars and transverse pins extending through said vertical flanges and strongly bearing against said bridge piece.

30 9. In a car-truck having a spring plank and inside hung brake-beams, inclined carrier or suspension bars for said beams, said bars having horizontal inner end portions extending below the spring plank; safety guard bars extending from the spring plank above the brake beams and detachably connected at their outer ends with the outer ends of the carrier bars, said guard bars having an inner portion at the upper surface of the spring plank, supporting means below the spring plank for detachably receiving endwise the inner end portions of the carrier bars and permitting their withdrawal, and clamping means at the upper side of the spring plank releasably securing the guard bars thereto.

10. In a car-truck having a spring plank and inside hung brake-beams, inclined carrier or suspension bars for said beams, said bars having horizontal inner end portions extending below the spring plank, safety guard bars extending from the spring plank above the brake beams and detachably connected at their outer ends with the outer ends of the carrier bars, said guard bars having an inner portion at the upper surface of the spring plank, supporting means below the spring plank for detachably receiving endwise the inner end portions of the carrier bars and permitting their withdrawal, and clamping means at the upper side of the spring plank releasably securing the guard bars thereto, said supporting means being a bracket secured to the spring plank and having open channels in its end portions to snugly admit and permit the withdrawal therefrom of the inner end portions of the carrier bars, and said bracket having at the inner ends of said channels an abutment for the inner ends of said carrier bars.

11. In a car-truck having a spring plank and inside hung brake-beams, inclined carrier or suspension bars for said beams, said bars having horizontal inner end portions extending below the spring plank, safety guard bars extending from the spring plank above the brake beams and detachably connected at their outer ends with the outer ends of the carrier bars, said guard bars having an inner portion at the upper surface of the spring plank, supporting means below the spring plank for detachably receiving endwise the inner end portions of the carrier bars and permitting their withdrawal, and clamping means at the upper side of the spring plank releasably securing the guard bars thereto, said supporting means being a bracket secured to the spring plank and having open channels in its end portions to snugly admit and permit the withdrawal therefrom of the inner end portions of the carrier bars.

12. In a car-truck having a spring plank and inside hung brake-beams, inclined carrier or suspension bars for said beams, said bars having horizontal inner end portions extending below the spring plank, safety guard bars extending from the spring plank above the brake beams and detachably connected at their outer ends with the outer ends of the carrier bars, said guard bars having an inner portion at the upper surface of the spring plank, supporting means below the spring plank for detachably receiving endwise the inner end portions of the carrier bars and permitting their withdrawal, and clamping means at the upper side of the spring plank releasably securing the guard bars thereto, said supporting means being a bracket secured to the spring plank and having open channels in its end portions to snugly admit and permit the withdrawal therefrom of the inner end portions of the carrier bars, and said bracket having at the inner ends of said channels an abutment for the inner ends of said carrier bars.

13. In a car-truck having a spring plank and inside hung brake-beams, inclined carrier or suspension bars for said beams, said bars having horizontal inner end portions extending below the spring plank, safety guard bars extending from the spring plank above the brake beams and detachably connected at their outer ends with the outer ends of the carrier bars, said guard bars having an inner portion at the upper surface of the spring plank, supporting means below the spring plank for detachably receiving endwise the inner end portions of the carrier bars and permitting their withdrawal, and clamping means at the upper side of the spring plank releasably securing the guard bars thereto, said supporting means being a bracket secured to the spring plank and having open channels in its end portions to snugly admit and permit the withdrawal therefrom of the inner end portions of the carrier bars.

14. In a car-truck having a spring plank and inside hung brake-beams, inclined carrier or suspension bars for said beams, said bars having horizontal inner end portions extending below the spring plank, safety guard bars extending from the spring plank above the brake beams and detachably connected at their outer ends with the outer ends of the carrier bars, said guard bars having an inner portion at the upper surface of the spring plank, supporting means below the spring plank for detachably receiving endwise the inner end portions of the carrier bars and permitting their withdrawal, and clamping means at the upper side of the spring plank releasably securing the guard bars thereto, said supporting means being a bracket secured to the spring plank and having open channels in its end portions to snugly admit and permit the withdrawal therefrom of the inner end portions of the carrier bars.

drawal and clamping means at the upper side of the spring plank releasably securing the guard bars thereto, said clamping means comprising parallel vertical flanges secured to the spring plank and snugly receiving between them the inner portion of the guard bars and oppositely apertured, and a transverse clamping pin extending

through said apertures above said inner portion of the guard bars and having a tapered 10 forward pilot end apertured to receive a cotter key and a head on its other end.

Signed at New York city, in the county of New York and State of New York, this 14th day of August A. D. 1924.

SETH A. CRONE.
